UNITED STATES PATENT OFFICE

MALCOLM S. JOHNSON, OF CHICAGO, ILLINOIS, ASSIGNOR TO ILLINOIS RAILWAY EQUIPMENT COMPANY, OF CHICAGO, ILLINOIS, A CORPORATION OF ILLINOIS

FLOOR RACK HOLDING MEANS

Application filed January 30, 1931. Serial No. 512,404.

My invention relates to means whereby the sections of a railroad car floor rack will be supported or held in raised position substantially parallel with the side walls of the car when the respective sections of the floor rack have been raised or swung upwardly off the car floor to permit cleaning of the car floor proper, or when need of the floor-rack is not required in the shipment of certain commodities.

As is well known, railroad car floor racks, used to provide an air circulating space between the car floor proper and the racks during shipment of perishable commodities, are usually made in separate sections to enable manipulation; and these sections are hinged-ly secured at one side to the car side wall or to the car floor adjacent to the car wall so as to permit the sections to be swung upwardly off the car floor.

My invention has for its object the provision of means adapted to be attached to a floor rack section at the pivoted or hinged side thereof where it is out of the way and therefore not located in the commodity receiving space of the car and consequently also where no damage or injury to the car loader or to the commodity can result.

The invention also has for its object the provision of a holder which is automatic in its operation and which will securely hold the floor rack sections in raised position and which at the same time can be readily released from holding position when the floor rack sections are to be dropped down onto the car floor; the means being attachable to the floor rack and not to the car walls where injury to the insulated walls is apt to occur.

The objects and advantages of my improved means will be readily comprehended from the detailed description of the accompanying drawings, wherein:—

Figure 1 is a sectional plan view of a portion of a railroad car and its floor rack sections, showing one of the floor rack sections in elevated position.

Figure 2 is an enlarged sectional view taken substantially on the line 2—2 of Figure 1, as viewed by the arrows.

Figure 3 is an enlarged sectional view taken

substantially on the line 3—3 of Figure 1, as viewed by the arrows, with my improved means moving toward rack holding position.

Figure 4 is a view similar to Figure 3 showing the means in rack holding position. 55

Figure 5 is a sectional view taken on the line 5—5 of Figure 4 as viewed by the arrows.

Figure 6 is a sectional view taken on the line 6—6 of Figure 4 as viewed by the arrows.

Figure 7 is a detail perspective view of the 60 attaching member of my improved means.

Figure 8 is a detail perspective view of the supporting member of my improved holding means.

Figure 9 is a detail perspective view of 65 the supporting member lock or controlling member.

Figure 10 is a sectional view of portions of a car floor, side wall and floor rack, illustrating a modified form of my invention in 70 non-holding position.

Figure 11 is a similar view showing the floor rack raised and my improved holder in elevation and in supporting position.

Figure 12 is a sectional view taken substantially on the line 12—12 of Figure 11 as viewed by the arrows. 75

My improved means is especially intended for supporting or holding the floor racks of a railroad refrigerator car in elevated or raised position along the side walls of the car when occasion arises for keeping the floor racks or any of the floor rack sections in such position. 80

As is well known, the floor racks are generally arranged in separate sections on opposite sides of the longitudinal center line of a railroad refrigerator car as illustrated in Figure 1, where a portion of a railroad car is shown at 15 with the floor rack sections, generally indicated at 16, arranged on opposite sides of the longitudinal center; the respective sections being usually hinged-ly secured at the wall sides of the sections, either to the side wall of the car or to the car floor adjacent to the side walls, in order that the sections may independently be folded upwardly. 85

That is to say, the floor racks are so hinged that they may be swung upwardly into posi- 90

tions substantially parallel with the car walls when occasion requires, as illustrated for example in Figure 1 where one of the sections is shown in elevated position.

- 5 The floor rack sections are composed of a suitable number of stringers 17 of comparatively heavy timbers, which are disposed longitudinally of the car in spaced relation and on which the slats 18 are superposed and secured; the slats being usually arranged in a predetermined spaced relation with each other so as to permit of the circulation of air therebetween as well as between the racks and the floor proper 19 of the car.
- 10 15 As my invention does not relate to the specific construction of the floor racks nor to the specific type of pivot or hinging means, a detail illustration of the hinges and further detailed description need not be entered into.
- 20 25 The stringers 17 of the floor racks are generally arranged in spaced relation transversely of the car, with the stringers at the hinge side of the floor rack sections generally disposed at a slight distance from the car side wall as shown in the drawings and with the vertical dimensions of the stringers somewhat greater than the extent of overlap or overhang of the slats at the inner hinged side of the rack sections, see Figure 2, thus permitting the floor rack sections to be swung upwardly toward the side wall of the car in the manner disclosed in Figures 3 and 4.

- 30 35 In order to clean the floor proper of a refrigerator car it is necessary from time to time to raise the floor racks up against the car side walls and to provide some sort of means whereby the floor rack sections will be maintained or held in elevated position. The securing of hooks in the car side wall is objectionable because the fastening bolts or screws tend to injure the insulation in the car side walls and the hooks are apt to damage merchandise or commodities or otherwise interfere in proper use of the car. I have devised means which are free of the objections referred to and which are intended to be secured to the underside of the floor racks, and particularly to the stringers, where such means will be out of the way in the normal use of the floor racks; while at the same time providing means which are more or less automatic in operation.

- 40 45 50 55 60 65 The specific exemplification of my improved means, as disclosed in the drawings, comprises an attaching member 20 which is shown in the nature of a plate provided with suitable apertures 21 for receiving the bolts 22, 22 whereby the attaching member 20 may be firmly secured on the side of the inner stringer 17 disposed toward the wall of the car. The member 20 is provided with a housing portion or enlargement 23 preferably provided with a non-circular opening 24 extending therethrough toward the opposite

side of the member, as shown in Figures 7 and 5.

The two opposite side walls of the housing portion 23 are provided with registering openings as at 25.

70 The opening or passage 24 of the housing portion 23 is intended to freely receive a lock member 26, shown in Figure 9, consisting of the shank portion 27 of configuration corresponding with the configuration of the passage 24, with the lower end thereof provided with the enlarged foot portion 28. The foot portion 28, on its lower side and intermediate of its ends, is provided with a transversely disposed groove or cut-away portion 29 preferably flared at the forward side, as shown at 30; while the rear end 31 of the foot portion is shown of somewhat less thickness than the front end 32 and the lower face of the end portion 31 preferably slightly tapered 80 upwardly toward the rear side of the lock member 26. The shank portion 27 of the lock member is provided with an oblong hole or slot 33 intended for the passage of a pin 34 therethrough. The upper end of the shank 90 95 100 105 110 115 120 125 130 135 140 145 150 155 160 165 170 175 180 185 190 195 200 205 210 215 220 225 230 235 240 245 250 255 260 265 270 275 280 285 290 295 300 305 26 and the latter has been moved outwardly through the action of the spring 36.

6 The distance between the rib 43 of the supporting member 38 and the bottom of the housing portion 23 of the attaching member is preferably just sufficient to permit the rib 43 to clear the rear end 31 of the lock member during swinging movement of the supporting member 38, but not sufficient to clear the forward end 32 of the foot portion 28 of the lock member 26.

10 This condition is provided so as to prevent the supporting member 38 dropping down or swinging too far forward when slight inward pressure is exerted on the lock member, and at the same time ensures the member being held out of way, as shown in Figure 3, during momentary movements of the floor rack sections until it is desired to be brought into action.

15 It is apparent that the groove or socket 29 in the bottom of the lock member 26 is of dimensions sufficient to receive the rib 43 of the supporting member and to permit the forward end 32 of the lock member to overlap the forward side of the bifurcated portion of the supporting member 38 so as to securely lock and hold the latter in position against the tendency of the raised floor rack section 20 to swing outwardly away from the car wall.

25 The pin 34 may be secured in place in any well known manner; and it will be understood that merely one of my improved holding means need be applied to each floor rack section, as for example at an intermediate point of a stringer namely at a point intermediate of the usual floor rack hinges shown at 45 which generally are also secured to the stringers as shown.

30 Where a floor rack section has been raised into vertical position, the supporting member 38 will be in the position shown in Figure 3 until the operator, with his foot, forces lock member 26 upwardly from its position in Figure 3, against the action of the spring 36, which allows supporting member 38 to swing, through the action of gravity, into vertical position.

35 The lock member 26 will then automatically move downwardly into locking engagement with the supporting member 38, as shown in Figure 4, and thereby hold the floor rack section in the raised position.

40 When the floor rack section is to be again lowered into place, the lock member 26 is raised against the action of its spring and the supporting member 38 is swung rearwardly until it clears the lock member, allowing the latter to return to normal position where it will hold the supporting member 38 in the non-supporting position shown in Figure 2.

45 In Figures 10 and 12, I illustrate a modified form, especially adapted to a floor rack which is hinged by what may be

termed a wall type of hinge as shown at 46; the hinge resting on the car floor 19 and against the car side wall as shown.

50 This form of my invention is especially adapted for floor racks hinged as shown because of the comparatively small amount of space between the inner stringer 17 and the car side wall.

55 This modified form is also intended to be secured to the wall facing side of the inner stringer 17 of the floor rack and involves an attaching member or housing 47 having apertured flanges or lobes to receive bolts 48 whereby the device is secured to the side face of the floor rack stringer 17. This housing 60 has a locking member 49 loosely mounted therein so it will drop or move downwardly through the action of gravity when the floor rack is raised upwardly against the car side wall as shown in Figures 11 and 12.

65 The shank portion of the lock member 49 and the opening through the housing or attaching member 47 are preferably of non-circular cross-section so as to prevent rotation of the locking member; and the shank 70 of the locking member 47 is provided with a vertically disposed oblong opening as at 50 (see Figure 12) to receive a bolt or pin 51 which extends through the two side walls of the housing 47. That is to say, the pin 75 51 is disposed in a direction at right angles to the direction of pin 34 in the previously described construction, and therefore in a direction transversely of the stringer 17 instead of lengthwise of the stringer as in the 80 structure shown in Figure 2.

85 The locking member 49 is provided at the bottom with a transversely enlarged foot portion 52, provided intermediate of its ends with a transversely extending socket 53 while 90 the ends of the foot portion 52 are preferably tapered or slightly curved toward the outer ends as shown in Figure 12.

95 Pendants disposed beneath the housing 47 and also beneath the locking member 49 100 is a supporting or floor-engaging member 54 of suitable construction, with its upper end bifurcated so as to provide the spaced apart portions 55, 55, adapted to extend parallel with opposite sides of the housing 47. The 105 upper ends of portions 55, 55 are apertured to receive the ends of pin 51, so as to swingingly support member 54 in place and permit the member to swing from its vertical floor 110 engaging and rack supporting position 115 shown in Figures 11 and 12 into a non-supporting position lengthwise of the floor rack stringer 17, as shown in Figure 10.

120 The pin 51 may be held in place by a suitable cotter pin as shown at 56.

125 The crotch or portion intermediate of the bifurcations 55, 55, of the supporting member 54, is made to enter the socket 53 in the foot 52 of the locking member 49 and this portion of member 49 is preferably made 130

- slightly sloping as shown at 57 in Figure 12 so as to abut against one side wall of the socket 53 in the locking member so as to prevent too far outward swinging movement of 5 the supporting member 54 when the floor rack is raised; while the other side wall of the socket 53 but slightly engages with the supporting member 54, just sufficient to hold member 54 in vertical position and consequently permitting member 54 to be released by a slight upward tap on the locking member by the foot of the operator.

It is apparent that the construction shown in Figures 10 to 12 can be applied to floor-racks which are closely hinged adjacent to the car side walls, without interference, because the supporting member will swing in a direction lengthwise of the floor-rack stringer when the floor-rack is to be lowered 15 onto the car floor. On the other hand, as the floor-rack is raised and the supporting means assumes a vertical position, the member 54 will swing downwardly and the locking member, through the action of gravity, will slide 20 downwardly into locking relation with member 54 and hold the latter in vertical rack supporting position.

I have illustrated what is believed to be the simplest embodiments of my invention 30 which have been described in terms employed merely as terms of description and not as terms of limitation, as structural modifications may be made without, however, departing from the spirit of my invention.

35 What I claim is:

1. Floor rack holding means comprising an attaching member adapted to be secured to the floor rack; a supporting member pivotally secured to said attaching member; and 40 a locking member carried by said attaching member adapted to normally form locking engagement with the supporting member.

2. Floor rack holding means comprising a member adapted to be secured to the floor 45 rack and provided with a socket; a supporting member pivotally secured to said first member so as to swing through a vertically disposed arc; and a locking member slidably mounted in the socket of the first member 50 and adapted to form locking engagement with the supporting member when the latter is in alignment therewith.

3. Floor rack holding means comprising a member adapted to be secured to the floor 55 rack and provided with a socket; a locking member slidably mounted in the socket; a supporting member; and means whereby the locking member is slidably held in said socket and the supporting member pivotally secured 60 to the first member.

4. Means of the character described comprising a member adapted to be secured to the floor rack and provided with a socket; a spring controlled locking member slidable 65 in said socket; a supporting member; the

locking member and supporting member being provided with interengaging surfaces; and means whereby the supporting member is pivotally secured to the first member.

5. Means of the character described comprising a member adapted to be secured to a floor-rack and provided with a socket; a locking member provided with a portion slidable in said socket and provided with an elongated opening therethrough; a supporting member provided with a bifurcated end adapted to straddle the locking member and the socketed portion of the first member; and a pin disposed through the bifurcated end of the supporting member, the socket portion of the first member and the elongated opening of the locking member, whereby the latter is slidably held in said socket and the supporting member pivotally mounted.

6. Floor rack holding means comprising a member adapted to be secured to a floor rack and provided with a socket; a locking member provided with a portion slidable in said socket and having an elongated opening therethrough; a supporting member having an upper bifurcated end adapted to receive said locking member while the bifurcations lap the sides of the socketed portion of the first member; a pin disposed through the bifurcations, the socketed portion of the first member and through the elongated opening of the locking member for slidably holding the latter in place and for pivotally securing the supporting member to the first member; and means whereby the locking member is normally forced into engagement with the supporting member.

7. Floor rack holding means comprising a member provided with a socketed housing and being adapted to be secured to a floor rack; a lock member located beneath said housing and having a shank portion slidable in the housing, said shank portion having an elongated opening therethrough, while the outer end of the lock member is provided with a transverse groove; a supporting member adapted to be disposed in alignment with the lock member and having spaced apart portions at its upper end adapted to straddle the lock member and the housing of the first member, the supporting member intermediate of the spaced apart portions being formed to enter the groove of the lock member; a pivot pin disposed through said spaced apart portions, said housing and the elongated opening in the lock member for slidably holding the latter in place and for pivotally securing the supporting member to the housing; and a spring mounted in said housing whereby the lock member is yieldingly held in locking position.

MALCOLM S. JOHNSON.
